UNITED STATES PATENT OFFICE

2,603,546

COMBINATION SERVICE AND OUTLET BOX

Henry L. Lais, Grand Forks, N. Dak.

Application August 29, 1949, Serial No. 112,998

3 Claims. (Cl. 312—100)

1

This invention relates to receptacles, and in particular to a receptacle adapted to be used as a combined service and outlet box.

An object of the invention is to position in one location power take-off outlets for electrical circuits requiring varying voltage and amperage.

Another object is to provide a novel weather-proof outlet box for outdoor use and suitable for farm yards, shops, granaries, barns and the like.

A still further object of the invention is to provide means for sealing the circuit breakers for various circuits against tampering by unauthorized individuals, that is simple in construction, cheap and easy to manufacture and assemble, strong, durable, and reliable in use, and pleasing in appearance.

These, together with various additional objects of the invention as will become apparent as the following description proceeds, are attained by this combined service and outlet box, a preferred embodiment of which has been illustrated by way of example only in the accompanying drawings, wherein:

Figure 1 is a perspective view of the invention showing the outlet box in its closed and locked position;

Figure 2 is a perspective view of the combined service and outlet box showing it with its outer cover raised;

Figure 3 is a vertical sectional view taken along line 3—3 in Figure 4;

Figure 4 is a vertical sectional view taken along line 4—4 in Figure 3;

Figure 5 is a horizontal sectional view taken along line 5—5 in Figure 4; and,

Figure 6 is a perspective view of the inner cover of the outlet box.

With continued reference to the accompanying drawings wherein like reference characters designate similar parts throughout the various views, reference numeral 10 generally designates the container comprising one element of the outlet box of the present invention. The container 10 includes a back panel 12, side panels 14 and 16 and the bottom panel 18. The bottom panel 18 has an upwardly extending flange 20 at the front edge thereof. These panels preferably are made integral with each other and are secured at the joints formed. They can be made by stamping from suitable sheet material.

An inner cover generally designated by numeral 22 is secured to the container 10 by bolts 24 passing through suitable apertures in the lower portions of the cover 22 and in the flange 20. The cover 22 is provided with an inwardly extending flange 26 at its bottom edge and flanges

28 and 30 at the side edges of the cover, flange 26 underlying the bottom, and flanges 28 and 30 overlying the respective sides of the container.

A top 32 having marginal downwardly extending flanges 34, 36, 38 and 40 is positioned on top of the container 12 with the flanges 36, 38 and 40 overlying the corresponding adjacent portions of said container and the flange 34 overlying the inner cover 22 to provide a water tight joint therefor.

An outer cover 42 is pivotally attached as by hinges 44 to a bar 46 secured to the outer face of the inner cover 22. The outer cover is dished outwardly as at 48 and is provided with a lock 50 of conventional design.

The top of the box is apertured centrally therethrough and a hub 52 is secured to the top 32 surrounding the aperture. The back panel 12 is provided with suitable mounting holes 54. These holes 54 are used to fasten the box to the surface on which it is to be mounted and enable the box to be set away from the surface on which it is to be mounted to allow air to circulate behind the box.

A grounding lug 56 comprising a copper bus bar with a pair of extensions 58 of connecting heavy neutral wires using solderless connectors is secured by Z-shaped supporters 60 in spaced relation to the back panel 12.

A plurality of knockouts are provided in the container, and inner cover to afford openings in the box through which wires must pass. There are three knockouts 62 cut in the back panel adjacent the bottom. A knockout 64 is provided in the back panel in the upper central portion. A pair of suitable knockouts 66 are located on each side of the box near the top. Four knockouts 68 of suitable size are provided in the bottom panel as is a larger knockout 70 which is centrally located therein.

A bracket 72 is welded to the back panel 12 and is adapted to hold the top of circuit breakers. These circuit breakers are provided with a lip 74 which fits under the bracket. Additionally, the circuit breakers are provided with holes 76 into which screws 78 are passed and secured to the back panel 12.

The circuit breakers 80, 82, 84, 86, 88, 90 and 92 are a safe and non-tamperable means of fusing, restoring, and operating a line load. By changing the combinations of circuit breakers a 110 volt, a 220 volt, single, or three phase operating combinations can be acquired. The breakers act as a fuse for the current going to the receptacles to be henceforth described.

Copper bus bars 94 are used for making com-

binations of circuit breakers to acquire different voltages and phases. The bus bars are tapped for screws 96 and are attached to the circuit breakers with these screws. Individual circuit breakers may be removed by removing screws 96 and 78. Solderless connectors 98 are used to connect main conductors to the bus bar. Load connectors 100 comprising solderless connectors are used to connect the load feeder conductors to the circuit breakers.

Three receptacles 102, 104 and 106 are used as a quick means of attaching rated loads. These receptacles are so grouped as to provide a combination of centrally located power and light outlets of varying loads and amperages.

Receptacle 102 is a polarized receptacle which can be used for heavy load appliances such as arc welders, large motors and so forth. Receptacle 104 is of smaller rating but can be used for similar purposes as that of receptacle 102. Receptacle 106 is not a polarized receptacle and is used for operating lighter loads such as small electric drills, motors, etc.

The circuit breakers are connected as desired to the receptacles in order to provide a readily available take-off connection for various predetermined loads. The main line from the power source may enter the box through the hub 52 prior to connection to the circuit breakers. The receptacles and circuit breakers are suitably grounded to grounding lug 56.

By means of suitable supporting bars 108 the receptacles are secured to the box. These bars 108 traverse the entire width of the box and are attached to the inner cover 22.

The inner cover 22 is provided with an inwardly dished central portion 110 which has a rectangular aperture 112 therein which allows the toggle switches 114 on the circuit breakers to protrude through the cover so that one can operate the circuit breakers without removing the outer cover. Round holes 116, 118, and 120 are provided on the cover 22, which allow the faces of the receptacles 102, 104 and 106 to protrude through the cover. An extended lip 122 for the cover is so designed as to slide up and under the top 32 so as to provide a water shedding fit at the sides and top of the box.

The recesses 110 and 48 in the inner and outer covers are in alignment and are so designed as to eliminate condensation from attacking the interior electrical connections in the box.

The exterior cover is attached to the interior cover to fill the requirements of outdoor installations. Thus, the necessity for having more than one style of box is eliminated. The outer cover is hinged as at 44 and these hinges are spring loaded to automatically close the cover.

Since from the foregoing, the construction and advantages of this combination service and outlet box are readily apparent, further description does not appear to be necessary.

However, since numerous modifications will occur to one skilled in the art after a consideration of the specification and accompanying drawings, it is not intended to limit the invention to the precise embodiment of outlet box shown and described.

except as required by the scope of the appended claims.

Having described the invention, what is claimed as new is:

- 5 1. An outlet box comprising a container having a back panel, side panels and a top panel, a front panel secured to said side and top panels and having an opening therein, an elongated substantially Z-shaped drain cap having spaced oppositely extending legs and a connecting web, means securing one of said legs to said front panel adjacent the upper edge of said opening therein, a cover overlying said opening and having the upper edge thereof disposed between the other of said legs and the front panel, and means hingedly attaching said cover to said last mentioned leg of said drain cap for vertical swinging movement.
- 10 2. An outlet box comprising a container having a back panel, side panels and a top panel, a front panel secured to said side and top panels and having an opening therein, an elongated substantially Z-shaped drain cap having spaced oppositely extending legs and a connecting web, means securing one of said legs to said front panel adjacent the upper edge of said opening therein, an outwardly dished cover overlying said opening and having an upwardly extending front panel engaging flange on its upper edge, said flange being disposed between the other of said legs of said cap and said front panel, and hinges attached to said last mentioned leg of said drain cap and to said cover adjacent the flange thereon, said hinges attaching said cover to said front panel for vertical swinging movement relative thereto.
- 15 3. An outlet box comprising a container having a back panel, side panels and a top panel, a front panel secured to said side and top panels and having an opening therein, an elongated substantially Z-shaped drain cap having spaced oppositely extending legs and a connecting web, means securing one of said legs to said front panel adjacent the upper edge of said opening therein, a cover overlying said opening and having the upper edge thereof disposed between the other of said legs and the front panel, and means hingedly attaching said cover to said last mentioned leg of said drain cap for vertical swinging movement, said top panel having downwardly extending flanges thereon overlying said back, front and side panels.
